FIG. 4.

FIG. 3.

FIG. 5.

To all whom it may concern:

Be it known that I, Louis W. Bonsib, a citizen of the United States, residing at Denver, county of Denver, State of Colorado, have invented a new, original, and ornamental Design for a Drive-in Restaurant, of which the following is a specification, reference being had to the accompanying drawing forming a part hereof.

Fig. 1 is a side elevation of a drive-in restaurant embodying my new design.

Fig. 2 is an elevational view of the side of the drive-in restaurant opposite the side shown in Fig. 1.

Fig. 3 is an end elevation of the same.

Fig. 4 is an elevational view of the end of the drive-in restaurant opposite the end shown in Fig. 3.

Fig. 5 is a top plan view of the drive-in restaurant.

I claim:

The ornamental design for a drive-in restaurant, as shown.
